J. KLINKHARDT AND W. KIBURZ, OF ST. LOUIS, MISSOURI, ASSIGNORS TO THEMSELVES AND PAUL OEHLER, OF SAME PLACE.

Letters Patent No. 84,284, dated November 24, 1868.

IMPROVED BRICK-MACHINE.

The Schedule referred to in these Letters Patent and making part of the same.

To all whom it may concern:

Be it known that we, J. KLINKHARDT and W. KIBURZ, of St. Louis, in the county of St. Louis, and State of Missouri, have made certain new and useful Improvements in Brick-Machines; and we do hereby declare that the following is a full and clear description thereof, reference being had to the accompanying drawings, and to the letters of reference marked thereon.

The nature of this invention is the arrangement of a double set of pressure-plungers, operating upon the clay in the moulds, and upon two different sides of the brick in its formation, thus insuring a sound and well-pressed brick, and one "true" on its several faces. In order to further insure a true lower face of the brick, we have arranged a cutter, which cuts off any swelling which may take place on the lower face during or immediately subsequent to the action of the pressure-plungers. The nature of our invention consists, furthermore, in certain detail construction of parts, to enable working-parts to receive "oil" or lubrication, and retain the same more perfectly than heretofore achieved in similar machines; all of which we will now more fully explain, in order that all those skilled herein may be enabled to make and use our said improved machine.

Of the accompanying drawings—

Figure 1 is a sectional elevation, and

Figure 2, a top plan.

Figure 3 is a detail enlarged section, showing the sliding plungers and arrangement thereon for "oiling," and

Figure 4 is a plan of a method of operating the sliding plungers.

A represents the pug-mill, which is supported upon standards in any suitable manner. The general form of the pug-mill is in nowise material. We arrange in the same the arms b, upon the vertical shaft B, to temper the clay when the mill is charged therewith. At the base, and near the circumference of the bottom of the pug-mill, is the discharge-opening a, leading to an inclined passage, a'. The screw-shaped scraper b, rotating with the shaft B, will force the clay down into the said passage, and the pressure hereof, with the pressure of the superimposed clay in the mill, will act to pack the clay tightly, and thus compress the same preparatorily in the passage a'. From said passage, by the continuous action of the screws b, the clay is forced into the mould-chamber C. This has three sides, c, which are permanent. The rear of the mould-chamber is formed by the pressure-plunger D, the top of the mould is formed by the pressure-plunger E, and the bottom is formed by the slide F. The several parts, c, D, E, and F, are so arranged that when the same are in the position to enclose the minimum space, this minimum of space shall be the circumscribed boundary of the compressed or moulded brick.

After the clay has descended from the passage a', the pressure-plunger is propelled forward, and cuts off

and forces forward a quantity of said partly-compressed clay, into the space directly under the plungers E. At the same time the bottom slide F moves forward, thus supporting the clay in its forward passage, and when the clay has reached its position in the mould proper, (under the plungers E,) the plungers E descend and compress the now enclosed body of clay. At the same time the rear plunger D has a slight forward motion, and thus, by the joint action of the plunger D and the plunger E, the clay is compressed and moulded, into proper shape.

Thereupon the slide F is drawn back, but the plungers D and E remain, and as now the bottom of the brick is released by the slide F, the clay may swell, and in order that this swelling may not produce an uneven surface, we arrange, in connection with said slide F, the cutters f. These remove, from the lower surface of the brick any swelling, and thus a true-faced brick is formed. When the cutters f have passed beyond the rear edge of the brick, the plungers E descend and force the brick out of the mould, and then the plunger D also returns.

The cutters f are connected with the slide F by suitable side bars, leaving a sufficient space for the swelling of the brick. The said cutters are therefore dependent upon the motion of the slide F, being operated by the devices operating the slide.

To operate the plungers E by the cam e on the driving-shaft G, the said cam being formed to give the said plungers the motion above described, to raise the plungers E when they have completed their downward stroke, we use the spring e', or any similar device which will raise the plungers quickly.

The driving-shaft G, by mitre-gearing, operates the centre shaft B of the pug-mill, and also the shaft H, which operates the plunger D and slide F. The cams h and h', on said shaft H, respectively act upon the rods d' and f' of the plunger D and slide F, to produce the forward motion hereof, as above described. A quick return motion is given to said parts D and F by the springs d'' and f'' respectively, which press against an abutment, d, and act by pins on said rods d' and f'.

The motion of said parts D and E may be achieved by a cam, x, acting upon a cam-yoke, x', which is connected with the rod moving the plungers, as indicated in fig. 4. In order that the plunger may be always held up to its pressure on the clay, even when the cam x has a certain amount of slip or play, caused by wear or any other inaccuracy of fitting, we use the spring x'', pressing upon the rod x' in opposite directions, and sustained by abutments x'.

It will be seen the plunger D, in its stroke, passes under the surface K. In order that the surfaces may be easily oiled, we have arranged the parts hollow, and the oil may therefore be thrown in at the opening, k, and it will pass down the oil-tube k', and lubricate a felt-lining piece, k''. It is plain that the upper surface

of the plunger D, from its contact with clay, would become solid, and that particles of clay would otherwise enter and choke the oil-passage l' . Similarly, to oil the surfaces of the plunger D and the slide F, the plunger is made hollow, and the oil passes through oil-tubes, l , upon the felt lining l' , to be therefrom distributed over the slide F. Similarly, the plungers E are made hollow, to receive oil, and this passes the oil-tubes m to the felt lining m' , and thus the felt is held moist. Now, as the plunger E presses the felt lining m' upon the clay below it, the oil is thus returned, being forced back. Upon release from pressure, oil again passes into the felt. It is our experience that the lining thus oiled produces a smooth surface upon the clay.

Having thus fully described our invention,
What we claim, is—

The arrangement and combination of the pug-mill A, its screw b and passage a' , with the mould-chamber C, and plungers D and E and slide F, substantially as set forth.

Also, the knife f , when combined and operated with the slide F, substantially as and for the purpose set forth.

J. KLINKHARDT.
W. KIBURZ.
